COMBINED JOURNAL BOX AND SEALING CLOSURE

Cleon M. Hannaford, Toledo, Ohio; Marie L. Hannaford executrix of said Cleon M. Hannaford, deceased

Application June 25, 1941, Serial No. 399,577

7 Claims. (Cl. 308—44)

This invention relates to journal box sealing means and more particularly to means for closing and sealing openings in journal boxes of railway rolling stock.

The invention comprehends the provision of closure means applicable for closing and sealing a journal box opening which provides access to the bearing proper for lubrication purposes and to a sealing closure means for the journal box opening which admits the dust guard for the car axle.

The invention comprehends the provision of a combined closure and sealing means for a journal box opening which will effectively prevent the ingress under all weather conditions of sand, dust, water, snow, ice and other foreign matter as well as to prevent the escape of lubricant from the journal box.

An object of the invention is the provision of a journal box and closure construction wherein the journal box and closure construction are so configurated as to form when in assembled relationship an effective seal for the journal box and wherein the closure is formed of a one-piece construction.

Another object of the invention is the provision of a closure or cover which may be applied to standard journal boxes now in use with slight modification of the journal box wall surrounding the opening in the journal box structure.

Further objects and advantages are within the scope of this invention such as relate to the arrangement, operation and function of the related elements of the structure, to various details of construction and to combinations of parts, elements per se, and to economies of manufacture and numerous other features as will be apparent from a consideration of the specification and drawing of a form of the invention, which may be preferred, in which

Figure 1 is a sectional elevational view through a journal box illustrating the closures for the journal box openings forming a part of my invention;

Figure 2 is an end view of the arrangement shown in Figure 1;

Figure 3 is a top plan view of a portion of the structure shown in Figure 1;

Figure 4 is a fragmentary sectional view taken substantially on the line 4—4 of Figure 1;

Figure 5 is a sectional view taken substantially on the line 5—5 of Figure 3;

Figure 6 is a sectional view similar to Figure 4 showing a modified form of my invention;

Figure 7 is a sectional view similar to Figure 5 showing a modified form of my invention.

Referring to the drawing in detail, 10 designates the journal box of a railway car having an upper wall 11 contacting a wedge plate 12, the latter in turn forming an abutment for the bearing brass 13 which directly contacts the car axle 14. The journal box is integrally formed with spaced vertically arranged ribs or guides 16 providing a groove to accommodate a dust guard 18, fabricated of wood or other suitable material which surrounds the car axle 14 at the point of its projection into the journal box.

As shown in Figures 1 and 2, the journal box 10 is provided with a rectangular opening 20 in the forward portion for the purpose of providing access to the interior thereof for purposes of inspection, repair and lubrication. Integrally formed with the upper wall of the journal box 10 and projecting upwardly are a pair of cylindrical bosses 21 joined by an irregular section 22, the bosses and section being bored to receive a hinge or pivot pin 24 upon which is pivoted or journalled a cover or closure 25. The hinge pin 24 is held in place by means of a key 23. The cover 25 for the opening 20 is preferably formed of sheet metal, as for example, steel or the like, and is provided with integral rectangular raised portions or flanges so configurated in cross section as to provide a channel shape having internal and external opposed re-entrant portions 27 and 28 forming a restricted throat, the re-entrant portions being adapted when the cover is hinged to closed position as indicated in Figure 1 to take over or grip the bead or ridge 26 formed integrally of the journal box and defining the opening therein, the re-entrant portions being formed of sheet metal are resilient and are slightly distorted when they are forced over the bead 26 and engage in the indented portions 29 and 30 of the bead 26 joined on the journal box forming a wedge-like seal therewith. The sheet metal cover 25 for the opening is of spring steel or is tempered to provide sufficient resiliency in the

rectangular raised portion and the re-entrant portions thereof for holding the cover tightly upon the beading surrounding the journal box opening and providing an effective seal therefor, as the throat formed by the re-entrant portions is normally of slightly lesser dimension than the thickness of the bead 26 as shown in Figure 4.

There is affixed to the sheet metal cover 25 a member 32 which is provided with a portion 33 arranged so that when the cover is in open position, it overtakes the section 22 intermediate the

cylindrical boss-like portions 21, the member 32 serving to hold the cover 25 in open position when it is desired to obtain access to the opening 20 in the journal box.

The upper portion of the journal box is provided with a rectangular opening 35 formed by the vertical ribs 16 to receive the dust guard. The walls of the journal box construction defining the opening are formed with a continuous bead or ridge 36 as shown in Figure 5. As part of my invention, I have provided a closure 37 for the dust guard opening which is preferably fabricated of sheet metal and configurated in cross section as shown in Figures 1 and 5 having a uniplanar portion 38 terminating in a continuous raised portion 39 forming a continuous groove adjacent the edge of the closure. As shown in Figure 5, the groove receives or takes over the beads or ridges 36 formed at the mouth of the journal box opening, the raised portion of the cover forming the groove or channel being configurated with re-entrant portions 40 and 41 forming a restricted throat similar to re-entrant portions 27 and 28 on the cover 25, the re-entrant portions of the restricted throat engaging in the complementary restricted portions 43 and 44 of the bead 36. When the closure 37 is in assembled relation with the journal box as shown in Figures 1, 3 and 5 the closure is tightly held in sealed position upon the journal box construction with the re-entrant portions 40 and 41 of the closure gripping the restricted portions 43 and 44 of the bead 36 to provide an effective seal for the dust guard opening 35. The closure is preferably formed of spring steel or is tempered to inherently embody a sufficient degree of resiliency or spring to hold the closure tightly in sealed position on the journal box.

In Figure 6 there is illustrated a modified form of closure for the lubrication opening in the journal box wherein the closure 48 is provided with a peripheral flange 49 having a re-entrant portion 50 forming an inwardly extending peripheral bead which is arranged to take over a bead or ridge 51 formed on the exterior wall of a portion of the journal box defining the lubrication opening therein, the re-entrant portion 50 of the closure engaging in a restriction or indentation 52 positioned adjacent the bead 51. The dimension between the opposing re-entrant portions 50 of the flange 49 is slightly less than the maximum dimension between the opposing exterior surface of the bead 51 formed on the journal box wall so that the re-entrant portions of the closure are distorted slightly when the same are forced over the bead 51. The resiliency in the sheet metal closure flange 49 and particularly the closure portion 50 is adequate to hold the closure in sealing engagement with the journal box to effectively seal the opening when the closure is in closed position.

Figure 7 illustrates the modified form of the invention as applied to a closure for the dust guard opening 25 in which the closure is provided with a uniplanar portion 55, a peripheral flange 56 which is formed with re-entrant portions 57 and 58 taking over the bead 59 formed on the journal box. The re-entrant portions 57 and 58 extend into the indentations or restrictions 60 and 61 formed on the journal box ribs 16' and when the closure is in assembled relationship with the journal box as shown in Figure 7 serves to effectively close and seal the dust guard opening.

It is apparent that, within the scope of the

invention, modifications and different arrangements may be made other than is herein disclosed, and the present disclosure is illustrative merely, the invention comprehending all variations thereof.

I claim:

1. In combination; a journal box having a substantially rectangular opening; said journal box having a bead defining said opening, said bead being joined integrally with the journal box by a wall portion having an indentation therein; a closure formed of sheet metal arranged to close the opening in said journal box; said closure being formed with a continuous peripheral integral configuration including re-entrant portions, said re-entrant portions adapted to be distorted and sprung over the exterior surface of the bead on said journal box and engage in and snugly fit the wall of the indentation therein when the closure is in closed position to effect the seal for the opening in the journal box.

2. In combination, a journal box having an opening; a bead integrally formed on said journal box surrounding said opening, the cross sectional configuration of said bead having a restricted portion integrally connecting the bead with the journal box; a closure formed of sheet metal pivotally connected to said journal box and arranged to close the opening therein, said closure having a raised channel shaped portion formed integrally therewith, said channel shaped portion having a restricted throat arranged to be distorted to fit over said bead and engage the restricted portion thereof when the closure is in closed position to effect a seal for the opening in the journal box.

3. In combination a journal box having a substantially rectangular opening; a bead integrally formed on said journal box surrounding said opening, the cross-sectional configuration of said bead having a restricted portion connecting the bead with the journal box; a closure formed of sheet metal arranged to close the opening in said journal box, said closure having a raised channel shaped configuration integrally formed therewith, said channel shaped configuration having a restricted throat arranged to be sprung over the bead of said journal box, the said restricted throat arranged to engage in and snugly fit the walls of the restricted portion of said bead when the closure is in closed position.

4. In combination a journal box having an opening; a bead integrally formed on said journal box and defining said opening, the cross-sectional configuration of said bead having a restricted portion connecting the bead with the journal box; a closure formed of sheet metal pivotally connected to the journal box and arranged to close the opening in said journal box, said closure being formed with a peripheral channel portion; the walls of said channel being provided with re-entrant portions forming a restricted throat; the throat of said channel portion being of a dimension slightly less than the width of the bead surrounding the journal box opening, the re-entrant portions of said throat being arranged to be slightly distorted and sprung over said bead to engage the restricted portion of said bead when the closure is in closed position to effect a seal for the opening in the journal box.

5. In combination a journal box having an opening; a bead integrally formed on said journal box and defining the opening therein; the cross-sectional configuration of said bead having a restricted portion connecting the bead with the

journal box; a closure formed of sheet metal pivotally connected to the journal box and arranged to close the opening therein, said closure having a peripheral flange projecting therefrom formed with a peripherally arranged inwardly extending bead; the dimension between opposed portions of the bead on said closure being of lesser dimension than the dimension between opposing portions of the bead on said journal box whereby the bead on said closure is slightly distorted and sprung over the bead on said journal box when the closure is moved to closed position.

6. In combination a journal box having an opening; a bead integrally formed on said journal box, the cross-sectional configuration of said bead having a restricted portion connecting the bead with the journal box; a closure for said opening formed of sheet metal and pivotally connected to said journal box, said closure having a raised portion configurated in cross-section to form opposed re-entrant portions, said re-entrant portions arranged to be distorted and forced over

the bead defining said journal box opening when the closure is moved to closed position to effect a seal for the opening in the journal box.

7. In combination a journal box having a substantially rectangular opening; a bead integrally formed on said journal box and defining said opening, the cross-sectional configuration of said bead having a restricted portion connecting the bead with the journal box; a closure formed of sheet metal arranged to close the opening in said journal box, said closure being formed with a channel portion having a restricted throat; the throat of said channel portion being of a dimension slightly less than the width of the bead surrounding the journal box opening, said throat portion being arranged to be slightly distorted and sprung over said bead to engage in and snugly fit the walls of the restricted portion of said bead when the closure is in closed position to effect a seal for the opening in the journal box.

CLEON M. HANNAFORD.
